UNITED STATES PATENT OFFICE.

THOMAS R. ARDEN, OF FOREST HILLS, NEW YORK, ASSIGNOR TO THE FERDINAND STRAUSS CORPORATION, OF NEW YORK, N. Y., A CORPORATION OF NEW YORK.

MECHANICAL JIGGER TOY.

Application filed May 28, 1926. Serial No. 112,253.

This invention relates to improvements in mechanical jigger toys and has for its main object the provision of a jiggling toy provided with a figure that will have a forward and rearward movement while jiggling.

Another object of the invention is to provide a toy of this character with an automatic reversing mechanism when the figure has reached the end of its movement in one direction.

A further object of this invention is to provide a toy of this character with a compensating or balancing spring that will sustain part of the weight of the figure.

Other objects and novel features of my invention will become more apparent as the specification proceeds.

Referring to the drawings forming a part of this specification:

Figure 1 is a front view in elevation of one embodiment of my invention with a portion of the front wall thereof broken away.

Fig. 2 is a top plan view partly in section taken on line 2—2 Fig. 1 and

Fig. 3 is a section taken on line 3—3 Fig. 2.

Referring to the drawings in detail, 5 indicates a framework or stage having a vertically extending wall 6 which may be suitably decorated, and a horizontal platform 7. A rod or shaft 8 is removably mounted longitudinally across the platform 7 in end walls 9 and 10 thereof. A frame or carriage 11 is slidably mounted on the shaft 8 and the frame 11 has a motor or propelling device 12 suitably mounted therein.

The motor 12 is provided with a power spring 13 one end of which is secured to a main drive gear 14 and the other end passes through an ear 15 struck up from a ratchet wheel 16 secured to a winding key shaft 17 that is journaled in front and rear walls 18 and 19 of the frame 11. The drive gear 14 is loosely mounted on the key shaft 17 and is provided with a hub or sleeve 20 rotatively mounted on a hub 21 of the ratchet wheel 16 that is rotatable in winding direction only and is so maintained by a pawl 22 mounted on a stud 23 journaled in the wall 19 of the frame 11. The pawl 22 is provided with two teeth 24 and 25 to insure positive engagement with the teeth of the ratchet wheel 16.

In an upper wall 26 of the frame 11 there is provided an annular bearing 27 in which

is revolvably mounted a disk 28 provided with an extending arm or projection 29 and a key slot 30. The annular bearing 27 has a flange 31 provided with stop faces 32 and 33, the object of which will be hereinafter described. Through the key slot 30 there passes a hollow stem 34 adapted to support two figures 35 and 36 joined together by a connecting piece 37 to which is secured a rod 38 that passes partway into the stem 34 and is supported thereon. The stem 34 is further provided with a disk 40 against which a tension is exerted by a compensating spring 41 which bears against the disk 40 and an ear 42 of the frame 11. This ear 42 also acting as a lower bearing for the stem 34 which is provided with a key projection 43 extending from the top of the said stem to the top surface of the disk 40 secured thereto.

To operate the toy the motor spring 13 is wound up by the winding key or shaft 17 and the drive gear 14 in mesh with a pinion 46 mounted on a square shaft 47 having mounted thereon at its forward end a pinion 48 in mesh with a rack 49 suspended from a spring 50 at one end and passing through clearance slots 51 and 52 in the platform 7. The rack 49 is provided with gear teeth on all sides of a slot 53. It will be seen by referring to Figs. 1 and 2 of the drawings that as the frame 11 is propelled in the direction of the arrows a star wheel 54 secured to the shaft 47 will actuate the stem carrying the figures 35 and 36 and produce a dancing or jiggling motion. Slot 55 in the top wall of the platform and slot 56 in the rear wall thereof allow the frame and figures to travel from one end of the platform to the other. When the figures have reached the end of the movement in the direction of the arrows as shown in Figs. 1 and 2, the movement and facing direction of the figures will be reversed. The reversal of the direction of movement is accomplished by the spring 50 which draws the rack 49 upwardly as soon as an extension 58 on the front wall 18 of the carriage 11 rides off an inwardly projecting flange 59 at the top of the rack member 49 allowing the lower teeth on the rack member to mesh with the pinion 48.

The reversal of the facing position of the figures is accomplished by the arm 29 on the disk 28 coming in contact with a lug or 110

abutment 60 on a bracket 61 secured at a predetermined point on the underside of the top wall of the platform 7. Likewise when the carriage and figures have reached the 5 opposite end of their movement, the pinion 48 will tilt the rack 49 downwardly at the opposite end of the spring 50 and will allow the extension 58 to ride over the flange 59 and the carriage and figures which have 10 been reversed by the arm 29 coming in contact with a lug 62 on a bracket 63 will again travel in the direction of the arrows in Figs. 1 and 2.

Gears 65 and 66 which are loosely mounted 15 on a shaft 67 loosely journaled in the carriage 11 act as a speed governor for the motor by means of pinions 68 and 69 fast to the gears 65 and 66 respectively, and meshing with gears 70 and 71 on the square 20 shaft 47. The gear 66 on the shaft 67 is in mesh with a pinion 72 fast to the gear 70.

From the foregoing it will be seen that I have provided a mechanical toy jigger which while dancing or jiggling will have 25 a simultaneous forward movement and when at the end of the said forward movement the carriage and figures carried thereon will reverse and travel in the opposite direction thus providing amusement for 30 children as well as adults.

The stop faces 32 and 33 act to limit the movement of the arm 29 when the position of the figures is being reversed from one position to the other.

35 Having described my invention, what I claim as new is:

1. A toy of the nature described, having a platform, a rack mounted in said platform, a carriage associated with the rack, a figure 40 mounted on said carriage, and a motor in engagement with the rack and figure mounted in said carriage to propel the same and to give the figure a simultaneous jiggling and forward movement.

45 2. A toy of the nature described, comprising a platform, a rod mounted in the said platform, a traveling carriage loosely mounted on the rod, a rack resiliently mounted on the platform, a figure revolvably mounted on the carriage, means on the carriage cooperating with the rack for reversing the travel of the carriage and means for reversing the position of the figure.

55 3. In a toy of the nature described, a platform, a carriage slidably mounted on the platform, a rack resiliently mounted on the platform, a motor to propel the carriage, a figure mounted on the carriage, means on the carriage coacting with the rack for reversing the travel of the carriage at a predetermined point of its travel, and means on the platform and carriage to simultaneously reverse the position of the figure.

65 4. In a toy of the nature described, a platform, a carriage slidably mounted on

the platform, a motor to propel the carriage, a disk revolvably mounted on the carriage, a stem providing means for movably supporting a toy figure slidably mounted in the disk, means for raising and lowering 70 the stem through the disk, an arm on the disk, means for reversing the travel of the carriage, and an abutment on the platform coacting with the arm to simultaneously reverse the position of the figure. 75

5. In a toy of the nature described, comprising a platform, a rack resiliently mounted on the platform, a rod mounted on the platform, a carriage loosely mounted on the rod, a toy figure mounted on the carriage, a motor to propel the carriage, and means on the carriage and rack for reversing the carriage at a predetermined point in its travel. 80

6. A toy of the nature described, comprising a platform, a rack yieldingly suspended from the platform, a rod mounted in the platform, a carriage slidably mounted on the rod, a toy figure mounted on the carriage, a motor mounted within the carriage and a pinion on said motor in mesh with the rack to propel the carriage along the rack and a projection on the carriage coacting with the rack to reverse the direction of the carriage at a predetermined point of its travel. 85

7. A toy of the nature described, comprising a platform, a rack supported on the platform, a rod mounted in the platform, a carriage slidably mounted on the rod, a toy figure mounted on the carriage, a motor mounted within the carriage, and a pinion on the motor in mesh with the rack to propel the carriage. 90

8. A toy of the nature described, comprising a platform, a rack yieldingly suspended from the platform, a rod mounted in the platform, a carriage slidably mounted on the rod, a motor mounted within the carriage, a pinion on said motor in mesh with the rack to propel the carriage along the 100 rack and reverse the direction of the carriage at a predetermined point of its travel, a stem vertically slideable on said carriage, a figure supported in the stem, a spring to compensate for a portion of the weight of the figure, a star wheel to actuate the sleeve in an up and down direction, an arm rotatably mounted on the carriage in engagement with the sleeve and an abutment on the 105 platform in the path of the arm to reverse the direction of the figure simultaneously with the reversal in direction of the carriage. 110

9. A toy of the nature described, comprising a platform, a rack yieldingly suspended from the platform, a rod mounted in the platform, a carriage slidably mounted on the rod, a motor mounted within the carriage, a pinion on said motor in mesh with the rack to propel the carriage along the rack, and reverse the direction of the carriage at a pre- 115 120 125 130

determined point of its travel, a stem vertically slidable on said carriage, a figure supported in the stem, a star wheel to actuate the sleeve in an up and down direction, an arm rotatably mounted on the carriage in engagement with the sleeve and an abutment on the platform in the path of the arm to reverse the direction of the figure simultaneously with the reversal in direction of the carriage.

10. In a toy, a platform, a rod mounted in said platform, a travelling carriage on the rod, a toy figure on the carriage, a rack resiliently mounted on the platform and means on the carriage cooperating with the rack to reverse the travel of the carriage at a predetermined point of its travel.

11. In a toy of the nature described, a platform, a rack resiliently mounted on the 20 platform, a carriage slidably mounted on the platform, a toy figure on the carriage, a motor to propel said carriage, and means on

the carriage coacting with the rack for reversing the travel of said carriage at a predetermined point of its travel.

25

12. In a mechanical toy, a platform, a rack on the platform, a motor mechanism slidably mounted on the platform, a figure connected to the motor mechanism, and means on the motor in engagement with the rack to bodily slide the motor mechanism and the figure connected therewith along the platform.

30

13. In a toy of the nature described, a travelling carriage, a spring motor mechanism to propel the carriage, a star wheel actuated by the motor, a slidingly mounted figure on the carriage actuated by the star wheel and a spring beneath the figure to compensate for part of the weight of the figure.

35

In testimony whereof I hereunto affix my signature.

THOMAS R. ARDEN.
